5 Claims. (Cl. 242—58)

This invention relates to the handling of paper rolls for feeding printing presses.

The principal object of the invention is to provide means for moving these heavy rolls in such a path that there will be no necessity of advancing and receding the center of oscillation of the web pressing means; to provide mechanism for handling a plurality of rolls in a small amount of floor space and to provide mechanism which will move the rolls in such a path that they can be brought readily to any desired point, it having been necessary heretofore to move the rolls in a circle.

Other objects and advantages of the invention will appear hereinafter.

Reference is to be had to the accompanying drawings, in which

Fig. 1 is an end view of a roll supporting and handling mechanism constructed in accordance with this invention, and

Fig. 2 is a front elevation.

Heretofore it has been necessary to mount one or more web rolls on a rotating reel or else on an oscillating support and thus confine the path of the web rolls to a circle or an arc of a circle and also take up a great deal of room. These rolls have to be moved to a position in which the paste can be applied. Then the web is forced against the roll. It has been necessary heretofore to rotate the reel or swing it by power along an arc up to a point adjacent to that at which the paster is to be made and then it has been necessary to move the web pressing means about its center a little forward or a little back in order to make the paster. As stated, the principal object of this invention is to provide an advancing means which will not necessitate the web pressing means being adjusted in this manner. It has been necessary also to move the web pasting mechanism back out of the way of the circularly advancing web roll at exactly the right time on account of the arcuate path of the web roll. According to this invention the path of the web roll during and directly after pasting is straight.

In the form shown two shafts 1 and 2 are rotatably mounted at one end on a pedestal 3 and at the other end on a pedestal 4. The pedestal 3 is fixed in position but the pedestal 4 is connected by a tongue and groove sliding arrangement O to a base plate 5. This permits this pedestal 4 to move sideways and give side adjustment for the side register of the web of paper going to the printing press. This is accomplished by the use of a motor 9 secured on

the base plate 5. On the shaft of the motor is a worm 8 meshing with a worm wheel 7 which carries on its shaft a screw 6 in threaded engagement with the pedestal 4. In this way, as stated, the side register can be accomplished. These pedestals constitute the frame for supporting the device.

The roll spindle 14 is carried in a pair of bearing boxes 10 which are made of two parts. The inner part constitutes a special link of a sprocket chain 11. Of course, one sprocket chain is used on each side of the machine. These sprocket chains are carried over sprockets 12 and 13 secured to the shafts 1 and 2 respectively said sprockets 12 being shown as larger in diameter than the sprockets 13. The bearing boxes 10 are furnished with an eye bolt and hand wheel arrangement 31 to keep them closed except when loading or unloading. The roll spindle 14 is supplied with cone collars 15 at its ends between which is mounted the paper web roll 16.

The shafts 1 and 2 are fixed by members 19 and 20 with respect to the movable pedestals so that they will move with it while these shafts have slideable bearings in the fixed pedestal so that as the moving pedestal is moved back and forth the shafts merely project more or less through the bearings on the fixed pedestal and the side register is altered. The worm wheel 19 and the collar 20 secured respectively to the shafts 2 and 1 ensure endwise movement of the mechanism when adjustment is made for side register.

The chains are operated by a motor 17 mounted on the pedestal 4 which through a worm 18 on its shaft operates a worm wheel 19 secured to the shaft 2. Of course, it will be understood that there are four or any desired number of these special links carrying the bearings 10 on each of the sprocket chains. The path of travel of these roll spindles 14 is not circular but of such a form that four bearings can be used for two fresh rolls and a running roll, and the other for taking on another roll. This structure takes up much less space than three rolls would on a cylindrical reel. The rolls travel in straight lines between the sprockets. This is especially important on the upper side where the path of travel makes a slight angle with the path of the web. In other words, the total space employed for the travel of one roll around the device is materially less than has been the case heretofore and much floor space is saved.

The invention is illustrated with an ordinary

- caterpillar tractor and belt 28 for speeding up the new roll and enough of the pasting mechanism is shown to illustrate how, when the new roll is brought to a predetermined distance from the brush 21, a solenoid 22 is energized, either by automatic means or by pressing a hand button, to lift a latch 23. This latch is normally in the path of a toe 24 but when lifted out of this path a spring 25 operates through a rod 26 and arm 27 to push the brush 21 on its pivot toward the new web roll. Thus it forces the traveling web W against the new roll 16 to make a splice. This mechanism can be mounted on a stationary frame 29, instead of a movable one as heretofore. After performing its function the brush is reset; that is, the latch 23 and the toe 24 are interengaged and the new running roll is brought down against the tension belts 33. Heretofore the whole brush mechanism had to be drawn out of the way of the first web roll, but now this is not necessary.

The details of the mechanism for running the new roll up to web speed and applying a paster does not constitute a part of this invention but are illustrated and mentioned to show the utility of the invention in connection therewith.

It will be obvious that the path of advance of the new roll is at a slight angle to that of the tension belts and the running web so the new roll can clear the brush mechanism easily and permit refined adjustment of the tension. The whole brush mechanism does not have to be drawn back to allow the new roll to pass.

Although I have illustrated and described only one form of the invention I am aware of the fact that modifications can be made therein by any person skilled in the art without departing from the scope of the invention as expressed in the claims. Therefore I do not wish to be limited in this respect but what I do claim is:—

1. In a web pasting device, the combination of means for guiding the web from an expiring roll along a path, a stationary frame, web pressing means movable on said frame, and a device for supporting both said expiring roll and a fresh web roll in a position so that said path is substantially tangent to the fresh roll, the said device being movable to carry the fresh roll to the expiring roll position along a path wherein the surface of the fresh roll will not cut across the path of the web pressing means or its frame.

2. In a web splicing device, the combination of means for guiding the web from an expiring roll along a path, a tension device for the web, a stationary frame, movable web pressing means carried by said frame, means for rotating the fresh roll up to web speed, and means for supporting said expiring roll and a fresh web roll in a position so that said path is substantially tangent to the fresh roll, the last named means being movable to carry the fresh roll to the expiring roll position along a path in a straight line converging with the path of the web at a point near the position of the expiring roll. 10

3. In a web splicing device, the combination with a web tension device along which the running web from an expiring roll runs, of a device for supporting at the same time the expiring roll and a fresh roll, means for moving the supporting device to move both rolls at the same time said supporting device having a straight 15 strand running from a position distant from the running web and the tension device by an amount equal to the radius of the fresh web roll to a position distant therefrom by an amount equal to the radius of the expiring roll. 20

4. In a web splicing device, the combination with a web tension device and means adjacent thereto for forcing the running web against a fresh web roll, of a fresh roll supporting and transferring device having means for supporting 30 a fresh and an expiring roll at a distance apart and having a straight strand movable in a straight line at an angle to the direction of the running web and tension device, the sine of which angle is substantially equal to the 35 radius of the fresh roll divided by the distance apart of the centers of the fresh and exhausting rolls on said straight strand.

5. In a web roll supporting and transferring device for a web splicing apparatus, the combination with means for applying a tension to a running web, said means extending in a straight line along the course of said web, and a movable support having means thereon spaced apart for carrying the running roll and a fresh roll, said 40 movable support having a straight strand making an angle with said straight line of the tension means, the size of which angle is substantially determined by the ratio between the radius of the fresh roll and the distance between 45 said two roll carrying means. 50
